UNITED STATES PATENT OFFICE

2,441,444

PRESSURE-REGULATING AND RETAINING
HANDLE FOR PORTABLE DRILLS

J. Taliesin Richards, Wilkes-Barre, Pa.; Catherine Richards, administratrix of said J. Taliesin Richards, deceased

Application October 31, 1945, Serial No. 625,725

4 Claims. (Cl. 77—14)

1

This invention relates to an improved pressure handle which is applicable to various types of portable pneumatic and electric drills, the same being adapted to replace or take the place of the ordinary or so-called pipe handle which is generally used, and embodying self-contained chain winding means, whereby, through the medium of said means and the work-embracing chain, constant pressure of the drill is maintained against the work to accomplish the drilling operation with expediency and reliability.

Novelty is also predicated upon a type of pressure handle in which the operator has complete control of pressure at all times and on nearing penetration by bit can control the pressure so that it will cut through the work without the likelihood of a kick-back.

This improved drill handle will enable the user to drill for long periods of time without fatigue, will insure constant follow-up pressure of the drill against the work, saves time and money, and is otherwise aptly fitted for the purposes intended.

At this point I desire to introduce the fact that the construction herein shown, described and claimed is possessed of improvements and refinements not disclosed in a patent covering a so-called pressure handle for pneumatic and electric portable drills granted to me under date of November 14, 1944, and identified as 2,362,929.

Briefly, the invention covered in my previous patent comprises a longitudinally elongated sleeve provided with an internal bushing and having a longitudinal slot at a predetermined point, a turnable hand-grip provided with a fitting telescopically and rotatably fitted in one end portion of said sleeve, a worm having shaft-ends located in said sleeve, one shaft-end being journaled in said fitting, means to maintain the fitting against longitudinal displacement from the sleeve, a casing including a tubular member surrounding said sleeve, said casing also including a gear housing provided with bearings, a worm gear mounted in said housing and provided with stub axles journaled in bearings in said housing, said worm gear having a peripheral portion thereof projecting through the slot in said sleeve, said worm being in mesh with the teeth on said gear, a cog wheel fixedly mounted on one of the stub axles of said worm gear, and a chain cooperable with the teeth of said cog wheel.

A primary purpose of the instant invention is to introduce certain refinements and special adaptations which, it is believed, represent improvements over the more complicated and fragile construction covered in the aforementioned pat-

2

ent. That is to say, I desire to do away with the bushing or sleeve 3 in the patent. Secondly, I improve the upper head construction of the gear casing or housing this being simplified to provide 5 sockets opening through opposite ends, one socket to accommodate the screw shank of an adapter plug, the opposite socket serving as a chamber for a short shaft on the handle, the latter being an integral part with the worm threads formed 10 thereon, instead of using the worm shaft 8 and bearing collar to the left of said shaft, as seen in the previous patent.

Other features and advantages of the invention will become more readily apparent from the following description and the accompanying illustrative drawings.

In the drawings wherein like numerals are employed to designate like parts throughout the same:

20 Figure 1 is a side elevational view of the improved pressure handle as designed in accordance with the present invention showing the same mounted, by an adapter plate, on one side of a conventional portable drill.

25 Figure 2 is a top plan view with the left-hand end portion broken away.

Figure 3 is a view, partly in section and partly in elevation, of the complete attachment, this to bring out the coacting relationship of parts, particularly the gearing.

Figure 4 is a fragmentary detail section on the short line 4—4 of Figure 1, parts being removed for clearness of illustration of this feature.

Figure 5 is a face view of the adapter plate.

35 Figure 6 is a view of the so-called "exploded" type showing the principal companion parts of the entire assembly.

Figure 7 is a section taken on the line 7—7 of Figure 2.

40 Referring now to the drawings by distinguishing reference numerals, attention is first directed to the handle unit 10. This comprises a hollow shell of one-piece form providing a hand-grip, the same being milled for effective handling, this

45 forming the hand-grip. Formed integrally and centrally with the left-hand end of the hand-grip is a relatively short, sturdy shaft 12 having spaced bearing collars 13 and 14, the collar 13 being adjacent the hand-grip, and both collars defining 50 an annular groove or channel 15 for the assembling screw 16. The left-hand end of the shaft is reduced in diameter to provide a stabilizing journal 17 and the remainder of the shaft is formed into a worm thread 18.

55 The chain drum and gear casing is, as a unit,

denoted by the numeral 19. This comprises a single casting having its body portion 20 (see Figure 3) fashioned to house a gear 21 mounted by its hub 21a for rotation on a stub-shaft 22 supported in a suitable bearing in the fixed side side wall 20a of the casing 20 (see Figure 7). The head portion of the casing, indicated at 23, is of general cylindrical form in cross-sectional shape. This is provided at its right-hand end with a bore which serves to accommodate the shaft 12 and parts embodied therein. This is brought out in Figure 3. That is to say, the bearing collars 13 and 14 fit snugly in the right-hand end portion of the bore and the reduced journal 17 is mounted in a centrally apertured partition at one end of the bore, thus providing a satisfactory bearing and assemblage of parts. The features are precision made so that the shaft can be slipped into the bore with ease and expediency. This is a manufacturing as well as a repair-making advantage. It is obvious that the adjacent portion of the chamber which accommodates the gear 21 communicates with a bore so as to permit the worm threads 18 to mesh with the teeth on the gear 21. It is also to be noted that one end of the stub-shaft 22 extends to the exterior of the casing 20 and this has the chain drum 24 suitably fastened thereon, the chain not being shown. The other end of said shaft 22 terminates flush with hub 21a and both parts unitarily fit into a bearing cup 32 at the center and provided therefor in a removable cover-disk 33 opposed to the wall 20a.

Also, as shown in Figure 3, a shorter socket is provided in the left-hand end of the head portion 23 of the unit 19. This is internally threaded to accommodate a screw-threaded shank 25 on the adapter fitting 26. This fitting has a screw-driver kerf 27 therein to facilitate application and removal.

The adapter plug 26 is intended to fit into a socket 28 (see Figure 5) carried by the adapter plate 29. This plate 29 is made to be fastened on a correspondingly shaped and proportioned mount 30 which forms an integral part of the portable drill 31. Incidentally, it may be mentioned that the structure herein shown is highly adaptable to be used on a heavy-duty electric drill such as that manufactured and sold under the trademark "Skilsaw." Picturing the latter type of drill, the usual cast one-piece handle (not shown here) is removed and the adapter plate 29 is put in place where it fits the stock part 30. Then the drill is ready to receive the improved pressure handle herein covered.

In reducing the invention to practice, I have evolved and produced a simple and expedient so-called pressure applying handle which is such in construction that one man can, through the use thereof, drill any size hole with ease and in less time than two or three men pushing or pulling, and can, at the same time, steady the drill while drilling holes head-high, overhead, underneath or on a ladder in comparative safety.

It is thought that persons skilled in the art to which the invention relates will be able to obtain a clear understanding of the invention after considering the description in connection with the drawings. Therefore, a more lengthy description is regarded as unnecessary.

Changes in shape, size and arrangement of the details coming within the field of invention claimed may be resorted to in actual practice so

long as they do not depart from the spirit of the invention or scope of the subjoined claims.

I claim:

1. As a component part of a pressure handle of the class described, a pressure regulating and retaining handle adapter plate for connection with a conventional portable drill, said plate being of general rectangular form provided on one face with a central accommodation socket, a screw-threaded fitting coacting with said socket, said fitting being provided with a screw-threaded shank adapted for accommodation of an associated part of said pressure handle.
- 15 2. In a structural assemblage of the class described, in combination, an adapter plate of general rectangular form, said adapter plate being adapted to be mounted on an existing stock surface on a portable electric drill, said adapter plate being provided with an internally screw-threaded socket, and a pressure handle attachment, said attachment including at one end a screw-threaded fitting, said fitting being screwed removably into said socket.
- 20 3. The structure specified in claim 2, said pressure handle attachment embodying a gear casing, gearing in said casing, a handle mounted on said casing for operating said gearing, said casing being provided with a screw-threaded socket and said fitting embodying a shank portion threaded into said last-named socket.
- 25 4. A pressure regulating and retaining handle for a portable drill comprising a one-piece casting including a substantially circular receptacle-like body portion constituting a gear casing, the latter being closed on one side and provided with a central bearing and open on the opposite side, a removable cover disk for said open side having a bearing cup axially aligned with said bearing, a gear confined and mounted for rotation in said
- 30 5. casing and having a hub mounted for rotation in said bearing cup, a stub shaft mounted in said hub and having one end terminating in flush relation with a corresponding end of said hub, the other end extending through and beyond said bearing to accommodate a chain drum, said casting further including an integral substantially cylindrical head, the latter having a smooth walled socket opening through one end of the head, a smaller screw-threaded socket in alignment with said first socket opening through the opposite end of said head, and a partition between said sockets having a bearing hole in alignment with said sockets, and a handle comprising a handgrip formed in one end with an integral
- 35 6. axially extending shaft, the outer end of said shaft being reduced and providing a journal, said journal being rotatable in the bearing in said partition, said shaft being provided with an integral worm thread confined in said first-named socket, said socket having an opening in communication with said gear casing, and the threads of said worm being in mesh with the teeth of said gear, and means for removably holding the shaft in said last-named socket.

J TALIESIN RICHARDS.
